CLAIM

The ornamental design for a coax cable connector, as shown and described.

DESCRIPTION

FIG. 1 is a top and front perspective view of a coax cable connector, showing my new design;

FIG. 2 is a side elevation view thereof;

FIG. 3 is a rear elevation view thereof; and,

FIG. 4 is a front elevation view thereof.

The broken lines in the drawings are for illustrative purposes only and form no part of the claimed design.
